(57) **CLAIM**

The ornamental design for a collapsible urine collection device, as shown and described.

DESCRIPTION

FIG. 1 is a perspective view of a collapsible urine collection device according to the new design;

FIG. 2 is a top view thereof;

FIG. 3 is a bottom view thereof;

FIG. 4 is a right side elevational view thereof;

FIG. 5 is a left side elevational view thereof;

FIG. 6 is a front elevational view thereof; and,

FIG. 7 is a rear elevational view thereof.

The broken lines shown in the figures illustrate environmental subject matter (i.e., an attached collapsible urine collection device) provided to assist in showing how the design may appear in use, and form no part of the claimed design.
